[57] **CLAIM**

The ornamental design for a lighting fixture for deck umbrella, as shown and described.

DESCRIPTION

FIG. 1 is a front perspective view of a first embodiment of a lighting fixture for a deck umbrella showing my new design;

FIG. 2 is a top plan view thereof;

FIG. 3 is a front elevational view thereof;

FIG. 4 is a side elevational view thereof;

FIG. 5 is a bottom plan view thereof;

FIG. 6 is a front perspective view of a second embodiment of a lighting fixture for a deck umbrella showing my new design distinguished from the first embodiment by having a different lamp socket arrangement;

FIG. 7 is a front elevational view of FIG. 6 hereof; and,
FIG. 8 is a bottom plan view of FIG. 6 hereof.
